UNITED STATES PATENT OFFICE.

WALTER S. GUYON, OF BROOKLYN, NEW YORK.

STREET-SWEEPER.

1,383,625. Specification of Letters Patent. Patented July 5, 1921.

Application filed March 7, 1917. Serial No. 152,995.

To all whom it may concern:

Be it known that I, WALTER S. GUYON, a citizen of the United States, and resident of borough of Brooklyn, city of New York, in the county of Kings and State of New York, have invented certain new and useful Improvements in Street-Sweepers, of which the following is a specification, reference being had therein to the accompanying drawing.

My present invention refers to new and useful improvements in street cleaning machines which are adapted to be operated by any suitable kind of gas engine or other motor, which engine will not only propel the entire machine but will actuate the sweepers or cleaners also.

The object of my improved motor sweeper is to provide a successful and complete street sweeping machine which is economical in its construction and efficient in its operation, having manifold adjustments to adapt the machine for different situations and having only as many parts as are necessary to produce the proper result; the machine being automatic throughout and performing a large variety of operations in picking up paper and refuse, sweeping dust, removing the sweepings, and then disposing of the collections in one continuous round of automatic mechanical operations so that the street, road or surface cleaned is left in an approved and satisfactory condition; and the invention, therefore, may be said to consist essentially in the combination, arrangement, and construction of the various mechanical parts to the end that the operation may be smooth and perfect substantially as will be hereinafter described and then more particularly pointed out in the claims.

In the accompanying drawings illustrating my invention:

Figure 1 is a side elevation of my improved street sweeper;

Fig. 2 is a top plan view of the driving connections and shows some of the other parts;

Fig. 3 is a sectional elevational view of certain details;

Fig. 4 is an enlarged detail side elevation of the main portion of the machine showing the sweeping devices and the dust collecting receptacles contiguous thereto, together with the means for operating them;

Fig. 5 is an enlarged detail side view of the operating mechanism for the brushes; Fig. 6 is an enlarged cross-sectional elevation of the brush and the means for actuating and adjusting the same;

Fig. 7 is a top plan view of the mechanism shown in Fig. 6;

Fig. 8 is a vertical sectional view of the elevating mechanism at the front of the machine for lifting the collections and dumping them into a receiving pan;

Fig. 9 is a detail sectional side view of a portion of the brush support;

Fig. 10 is a detail view in plan showing the mechanism through which the bucket that lifts and discharges the dirt into the collecting bin of the machine is moved back to its lowermost, collecting, position.

Similar characters of reference designate corresponding parts throughout the different figures of the drawing.

The general frame of the machine consists of a suitable horizontal rectangular skeleton structure adapted to accommodate therein and therewith various mechanical features, said frame being preferably as to one portion thereof, say the rear half, as 1, somewhat higher than the other half or front portion, as 2, since such a shape lends itself more easily to the function of properly supporting the various related parts; said rear higher portion 1 carrying thereon a motor 3, which may be a gasoline or other engine arranged to actuate a longitudinal shaft 4 above the frame 1, and having thereon a clutch device 10 operated by a handle 11 and a clutch device 12 operated by a handle 13, which clutches serve to throw the shaft into and out of action in various ways to be hereinafter explained. The clutch 10 is connected to a bevel gear wheel 14 which meshes with a bevel gear wheel 15, while the clutch 12 operates a bevel gear wheel 16 that meshes with a bevel gear wheel 17 on a vertical shaft 18, these gear wheels 15 and 17 having the function of driving certain of the parts, as I shall hereinafter more fully set forth.

The front portion 2 of the frame carries a large hopper or receptacle 6 having a cover 7 provided with a handle 9, said cover being pivotally hung at 100 on the elevator casing 8 or elsewhere. The receptacle 6 is movably mounted on platform 2 by links 101, and said receptacle is designed to re-

ceive and carry the sweepings and other collections from the street, there being along-side of the hopper 6 in the rear thereof, the elevator casing 8 containing a chain ele- 5 vator 19, as shown in the sectional view in Fig. 8, and the details of which will be hereinafter more fully explained. Further, it will be understood that the main frame 1 and 2 is provided with front wheels *a* and 10 rear wheels *a'*, of which obviously there may be any desired number, for example two at front and rear, as illustrated, or any other number, for properly supporting the frame, the mechanical parts and the burden. 15 Some of these wheels, as, for example, the front wheels *a* are directly driven by connection with the motor 3 in order to furnish propelling power for the street sweeping machine along the surface of the street 20 or road on which it is operated. The bevel gear wheel 15, which I have stated is at the forward end of the frame section 1 and contiguous to the elevator casing 8, is mounted on the upper end of a vertical shaft 20 (see Fig. 2) which carries a 25 bevel gear wheel 21 (see Fig. 3) on its lower end, which meshes with bevel gear wheels 22 adapted to be clutched by the clutches 23 and 24 to one or the other of the horizontal 30 transverse shaft sections 25 (see Fig. 2), on the opposite ends of which are sprocket wheels 26 and 27. From the sprocket wheels 26 and 27 run chains 28 on the two sides of the machine, which chains pass around 35 sprocket wheels 29 on the shaft 30 that carries the front driven wheels *a*, *a'*. In this way it will be seen that power is communicated from the motor 3 to the front wheels *a* for the purpose of actuating the latter and 40 propelling the machine on the road. The machine is driven in one direction by using the clutch 23 and in the opposite direction by using the clutch 24. In the arrangement of gearing shown in the drawings the 45 machine is driven in a forward direction when the clutch 23 is operated to connect its shaft section 25 with the motor-driven gearing. This driven impulse is communicated either on one or both sides of the machine, usually only on one side at one time, the connections being controlled as aforesaid by the clutch devices 23 and 24, (and also the clutch devices 31) whereby the shaft sections 25 are thrown into and out of ac- 50 tion, so that the latter may be idle or effective, and in this connection it may be observed that obviously all these clutch devices 23, 24 and 31 will be equipped with proper operating levers so that the attendant may 55 control the movement of the different parts of the mechanism. The means for controlling these clutches, as also the levers 11 and 13 which control the clutches 10 and 12, will 60 preferably be located in convenient proximity to the seat 5 of the driver which is 65 mounted on the frame section 1 as indicated in Fig. 1.

It will be noted that on the shaft 30 of the front wheels *a* is another sprocket wheel 102 around which passes a chain 32 that 70 engages a sprocket wheel 33 on a shaft 34 which is mounted in standards below the front portion 2 of the main frame. On the ends of this shaft 34 are sprocket wheels 35 around which pass chains 36 that likewise 75 pass around sprocket wheels 37 on a front horizontal transverse shaft 38 that is supported in brackets 39 carried by the front portion 2 of the main frame. Below the front portion 2 of the main frame is a basket 80 40 extending transversely across the frame at a short distance above the ground, and extending forwardly from said basket is a series of rigid fingers 41 which project down toward the ground and assist in picking up 85 paper and various large objects, that is to say, which assist in combing the surface of the street in advance of the sweeping brushes for the purpose of collecting such of the refuse material that may be upon the street 90 that is possible to gather in this manner, and thus relieve the brush from the work of handling the heavier articles. Operating with these rigid fingers are two or more rakes 42 consisting of cross-rods secured to 95 and carried by the chains 36, said cross-rods having a series of teeth that are staggered with respect to the fingers 41, see Fig. 2.

The elevator casing 8 which is supported on the front part 2 of the main frame just 100 behind the receptacle 6 protects and incloses the vertically movable chains 19, one at each side of the machine, shown in the enlarged view in Fig. 8 and running around the lower sprocket wheels 42 on the shaft 43 carried 105 in brackets 44 secured below the platform 2, said chains 19 also passing around upper sprocket wheels 45 carried on a horizontal shaft 46 that is journaled in the sides of the casing 8. The chains 19 are driven by the 110 sprocket wheels 45, which are driven by outside inclined chains 47 passing around sprocket wheels 48 likewise on the shaft 46 and also around sprocket wheels 26^a on the lower shaft 25 which is directly driven by a gear- 115 ing connection with the main engine shaft 4 as already explained. The chain or chains 19 carry a transverse bucket or buckets 49 suitably pivoted thereto at 50, see Fig. 8, and as the chains 19 move upwardly they carry 120 with them the bucket 49 which is caused to occupy different positions by virtue of a guiding track 51 against which it slides. Said bucket is also provided at its rear side with a hook 52 and it has an open mouth 53. 125 When the bucket is in its bottom position, its mouth 53 is so situated that it is open to receive quantities of sweepings delivered thereinto by a main shovel device 54 which I shall presently explain. As bucket 49 130

travels upwardly, however, it is turned on its pivot 50 so that its open end 53 will be uppermost while its heavy round end 51^a will be at the bottom, and the side 51^b which 5 carries the hook 52 will slide against the vertical wall of the guide 51. The chains 19 may also be guided by suitable channeled uprights, as at 103, if desired. The bucket 49 will continue in this position until it reaches the top of its course through which 10 the lifting chains 19 travel, and when it gets to the top and the bucket 49 is lifted over the shaft 46, said shaft will be engaged by the hook or hooks 52, and this will stop the further movement of the bucket 1 at the moment when its mouth 53 is directly over the receptacle 6 and the contents of the bucket 49 will consequently at this time be dumped into the receptacle 6. It will be understood 15 that this bucket is operated intermittently by leverage devices applied to the clutches 31 or any other instrumentality by means of which motion may be temporarily communicated from the shaft sections 25 to the chain 20 47 for the purpose of driving the elevating chains 19 long enough to lift the bucket 49 from its lowermost position, as shown in full lines at the bottom of Fig. 8, to its uppermost dumping position, as shown in dotted 25 lines in the upper part of Fig. 8. A reverse movement of the chains 19 which can be accomplished by suitable lever and clutch mechanisms replaces the empty bucket 49 at the bottom of its vertical travel in the 30 position shown in Fig. 8 where it is in readiness to be again filled with the sweepings collected by the shovel. To secure this reverse movement the mechanism illustrated in Fig. 10 may be employed. In this view 35 the shaft section 25 is the one employed for reverse driving of the machine. The sprocket wheel 26, connected, by the chain 28 with the shaft of the drive wheels, is loose upon the shaft section 25, but is 40 adapted to be connected therewith by a clutch 26^b. Supposing now that the machine is moving in a forward direction and that the bucket 49 has been filled and the operator wishes to empty its contents into the 45 bin 6. He will, through the clutch 31, connect the forwardly driving shaft section 25 with the sprocket wheel 26^a to cause the lifting chains 19 to be driven and the bucket 49 elevated into discharging position as represented in dotted lines in Fig. 8. As soon 50 as it reaches this position the clutch 31 is disengaged. To reverse the movement of the bucket, moving it back to loading position, the other clutch 31, on the rearwardly 55 driving shaft section 25 is operated. As it is desirable that this reverse movement should take place without stopping the forward movement of the machine, I interpose, 60 between the shaft section 25 and the sprocket wheel 26, which is loosely supported upon 65 such shaft section, a clutch 25^b which is only used when it is desired to drive the machine in a reverse direction, and hence to connect the shaft 30 on which are supported the drive wheels with the power train through 70 the reverse driving shaft section 25 and clutch 24. The clutches 31, 31 on the shaft sections 25 are preferably friction clutches, and I operate one of them for the purpose of driving the chains 47 in one direction so 75 as to lift the bucket 49 to its uppermost dumping position, at which time the hook 52 is in engagement with the shaft 46; and then I operate the other clutch 31 which connects with the other shaft section 25 that is revolving in the opposite direction, and in this way I am able to drive the chains 19 in the reverse direction and bring the bucket 49 back down from its top dumping position to its lower receiving position, as shown in 80 full lines in Fig. 8.

54 designates a shovel which is of large and substantial construction, and which extends transversely across the machine, as shown in Fig. 7, having a scoop shape and 85 being designed to drag along on the ground just in the rear of the receiving elevator bucket 49. Shovel 54 is suitably carried by a shaft 56 journaled in the bracket 57 attached to the platform 2, which shaft 56 is 90 provided at the ends with crank arms 58, see Fig. 4, to which arms 58 are attached chains 59 running around pulleys 60 and fastened to hooks 61 that slide in guides 62. These guides 62 have rigid pins 63 that 95 enter a slot 64 in the hooks 61. The forward ends of the hooks are designed to engage pins 65 with which a certain number of links 66 are provided, said links belonging to endless chains 69 that are operated 100 for the purpose of actuating the brushes 55 carried in brush heads 55^a, the details of said brushes being indicated in Fig. 9. It will be obvious that the brushes 55 as they 105 brush along on the surface of the street in the direction shown by the arrow in the bottom of Fig. 4 and while the machine is moving in a forward direction, will sweep the dirt into the shovel 54 when the latter occupies its lower position, as indicated in 110 dotted lines in said figure. At certain points in the progress of the brushes the pins 65 with which certain of the links 66 are provided will be engaged by the hooks 61, and the hooks will be carried along in 115 the movement of the brushes, thus drawing on the chains 59 and turning the crank arms 58 and shaft 56, thereby lifting the shovel 54 by the rotation of shaft 56 and causing it to turn over and dump into the open mouth 53 of the bucket 49, all as indicated in Fig. 4. When the shovel or scoop 54 has 120 been lifted to its dumping position, as shown in full lines in Fig. 4, it is held there long enough to discharge its contents, and 125

then the hooks 61 will come into contact with the projections 104 on the main frame, and the beveled faces of said hooks will slide on the projections 104, thereby lifting the hooks sufficiently to clear them from the pins 65, whereupon the weight of the shovel will cause it to drop again into its dragging position where it receives the collections of the brushes.

10 The brush heads 55^a are provided with pairs of antifriction rollers 72, each of which has a short shaft 105, one end of which shaft is journaled in the brush head 55^a, as shown in Figs. 6 and 9, while the 15 other end is carried by a link 106 of the brush-carrying chains 69, several links of said chains, say four of each, as shown in Figs. 4 and 5, being properly enlarged and perforated to permit the reception of the 20 ends of the shaft 105 therein. The rollers 72 operate between the sides 71 of the main frame and the channeled guides 70 which are secured to said sides 71 at a short distance above and below the same by means 25 of the outwardly-projecting straps 74 which are of proper size and shape to allow the chains 69 to operate freely through them. The chains 69 are located, one at each side of the machine, and they carry the shafts 30 105 and their rollers 72, as also the brushes 55 supported thereby, as I have explained; and these chains 69 are driven by means of sprocket wheels 79 around which said chains 69 pass, as shown in Fig. 4. These 35 sprocket wheels 79 are mounted on horizontal transverse shafts 73 that are supported in sockets 77 on the lower ends of vertically-adjustable rods 76, which pass upwardly through bearings 78 that are bolted or otherwise firmly attached to the main frame section 1 (see Fig. 4); also to the ends of the shafts 73 outside of the vertically-movable guide rods 76 are pivotally attached vertical links 96, whose upper ends are pivoted 40 to horizontal levers 94, that are fulcrumed on brackets 95 secured to the main frame 1 and projecting below the same, the inner opposite ends of the horizontal levers 94 being pivoted to vertical links 93 whose upper ends are pivotally attached to a link block 50 92, which in turn is pivoted to a link 91 that is also pivotally attached to an arm 90 secured to a shaft 85, to which shaft is also attached a lever 84. The shaft 85 is held in 55 bearings on the top of the frame 1, said shaft 85 being a horizontal shaft that passes across the machine. Hence, the connections 90, 91, 92, 93, 94, and 96 are duplicated on both sides of the machine, so that the whole 60 mechanism may be operative by the lever 84, which is arranged contiguous to the driver's seat 5 for the purpose of enabling the brushes 55 to be raised and lowered at will and thus adjusted with relation to the 65 surface of the street and thus caused to bear

thereon more heavily or more lightly, as may be required. The blocks 92 are each provided with an upwardly extending rod 87 which slides through a bearing 86 on the top of frame 1. Also the shaft 85 is provided with a rigid arm 88 carrying a counterweight 89 to make the operation of the lever 84 quicker and easier. It is further to be noted that on the shaft 73 outside of the straps 74 and the chains 69 are secured 75 sprocket wheels 80 around which pass chains 81 (see Figs. 1, 4, and 6) that likewise pass around the drive sprocket wheels 82 firmly mounted on a horizontal shaft 83 which in turn, as shown in Fig. 2, is connected by 80 suitable gearing, as for example bevel gears which are operated by the bevel gears 16 and 17 and the clutch 12, by means of which the impulse gathered from the rotation of the main shaft 4 is transmitted to operate the 85 brush chain 69 and drive the brushes with sweeping effect, all these parts being relatively arranged and combined for joint operation, but susceptible of various modifications in actual practice in order that the best 90 results may be secured. It will also be noted that the sides 71 of the frame belonging to the mechanism for carrying and raising and lowering the brush are connected together by suitable cross braces, as for example, the braces 75 indicated in Fig. 7, though substitute supports and braces may be employed if needed.

From the foregoing description of the construction and relative arrangement of the 100 various parts, the operation will be clearly understood. It will be seen that my improved sweeper provides a mechanism whereby the surface of the street may be effectually cleaned by a dry brush and the 105 sweepings quickly, industriously, and automatically taken directly from the brush and conveyed by a series of appropriate mechanical operations performed in a unitary apparatus to a bin or receptacle of considerable capacity, which only needs an occasional emptying so that the apparatus may be operated for a long time before said bin requires to be discharged. By supporting the mechanism and driving it also in the 110 way I have described, a motor apparatus is provided which can be operated economically on any kind of a surface which it is desired to clean at any desired speed and with an adjustment for the brushes which 115 is easily variable to suit varying conditions. The operator has everything completely and immediately under his control and at his hand from the use of the various levers arranged in close proximity to the seat.

When the machine is first set into operation, the necessary clutches, levers, etc. are utilized for that purpose, and ordinarily I find it best to drive the machine forwardly though the use of the gears, chains, and 120

other connections on one side of the machine, as for example, one of the shaft sections 25, the chain 28 and sprocket wheels 26 and 29; while on the other hand when 5 it is desired to reverse the machine I employ the driving connections on the other side, as for example, the shaft section 25 and sprocket wheels 27, 29, and chain 28, in these instances the power being applied, as 10 is easily seen to the front drivers a , a' . While the machine is moving forward moreover, the rigid fingers 41 which constitute a projecting comb, are in position close to the surface of the street, and the rakes 42 15 are revolving rapidly and picking up all large articles on the street and transferring them into the cage 40, so that in advance of the machine the street is effectively cleared of the largest part of the debris, leaving the 20 brushes to apply their rubbing effect to the street surface to take up the smaller particles of dirt, dust, etc. When in the course of the progress of the machine the attendant observes that the shovel 54 has delivered 25 into the bucket 49, he will operate the proper clutch 31 and cause said bucket 49 to be lifted and discharged into the hopper 6, and when so discharged he will operate another proper clutch and cause the bucket 49 30 to be carried down again to its bottom position at the lower end of the guide track or tracks 51, where it is in readiness to receive the next automatic dumping of the shovel. The shovel is filled, of course, again 35 and again by the brushes sweeping the refuse into it. Furthermore the operator by a manipulation of the handle 84 is able to raise and lower the frame which carries the brushes and cause them to be placed nearer 40 to or farther away from the surface that is being cleaned. This is a great advantage, and when taken in conjunction with the automatic shovel and the lifting bucket, a series of mechanical functions is employed 45 which not only has unusual novelty, but makes it possible for a single machine to do an immense amount of work and to displace a great deal of labor now employed by hand.

50 It will be noted that I have represented many of the parts in outline merely, especially where they consist of gears and transmitting and connecting means, since it is possible to arrange these parts in a large 55 variety of different ways, and I wish the entire liberty of applying and relating these parts in the best way to accomplish the end in view; and further it is insisted upon that in the actual development and practical operation of the machine I shall have the right 60 to make all the changes needed to perform the best results and to carry my invention into effect in the most successful way, provided only I do not exceed the scope of the 65 appended claims. Referring again to the

brushes or sweepers 55 which are located transversely of the machine and are carried in brush heads 55^a, it will be understood that the length of these brush heads and consequently the effective sweeping area of 70 the brushes may be of greater or less length, but usually I prefer to have these brushes extend clear across the machine so that the ends thereof, as indicated in the drawings, may be directly in line with the tracks made 75 by the wheels a , a' or a , a' , either one or both sets, in order that the end of the brush may operate in the gutter close up against the curb without leaving any unclean space at that point. This is an important feature 80 in the construction and location of the brush, and I desire to lay stress thereon in the description.

Having thus described my invention, what I claim as new and desire to secure by Letters Patent, is:—

1. In a street sweeper, the combination of a main frame, a brush, a brush-head on which it is mounted, antifriction rollers, each having a shaft, one end of which enters 90 the brush head, an endless chain having certain of its links perforated to receive the other ends of the roller shafts, wheels supporting the said chain, a frame in which said wheels are mounted, said frame having 95 channels in which the said antifriction rollers operate, means for driving the chain, means for raising and lowering the said frame, and guiding means for said frame in its up and down movement, consisting 100 of vertical rods working through sockets on the main frame.

2. In a street sweeper, the combination of a main frame, a brush, an endless traveler to which it is attached, means for driving the 105 traveler, means for raising and lowering the traveler, said latter means including an operating lever and a system of levers operated by said operating lever, and vertical guides for the means which raises and lowers 110 the traveler, consisting of vertically-movable rods and sockets on the main frame which receive and guide said rods.

3. In a street sweeper, the combination of a brush, a chain for driving it, a movable 115 frame, wheels journaled in said frame for supporting the chain, antifriction rollers in channels in said frame, which rollers are attached to the brush and to the chain, outwardly projecting straps within which the 120 chains operate freely, said straps being attached to the movable frame, means for raising and lowering said frame and contiguous parts, said means including a system of levers and an operating hand lever, vertical 125 guide rods for the said movable frame, a main frame, and sockets thereon for said guide rods.

4. In a street sweeper, the combination of sweepers, an endless traveling chain carry- 130

ing said sweepers, means for supporting and guiding said chain, leverage means for adjusting said supporting means so that the sweepers may be brought into proper relation with the surface being swept, a movable shovel which receives the sweepings, and a 5 detent for controlling the movements of the shovel to cause it to discharge the sweepings and which engages the sweeper-carrying 10 vice at times and is released therefrom at other times.

5. In a street sweeper, the combination of sweepers, an endless traveling chain carrying said sweepers, means for supporting and 15 guiding said chain, leverage means for adjusting said supporting means up and down, a pivoted shovel which receives the sweepings, a hook arranged to engage pins projecting from the endless chain, said hook 20 having an inclined face, a stationary releasing pin for said hook when the inclined face strikes said pin, and a connection between said hook and the shovel.

6. In a street sweeper, the combination of 25 a brush, an endless chain carrying the brush and having projections thereon, a frame in which the chain is supported, means for raising and lowering the frame, a pivoted shovel which receives the sweepings from the brush, 30 said shovel having a crank arm, a hook adapted to engage projections on the chain and having an inclined releasing edge and a slotted body, a stationary pin which releases the hook from the pins on the chain 35 when the inclined edge strikes said stationary pin, a stationary bracket engaging the slotted body of the hook, and a connection between said hook and the crank arm on the shovel.

40 7. In a street sweeping apparatus, the combination of a main frame, brushes, endless chains carrying the same, sprocket wheels supporting said chains, a frame in which said sprocket wheels are journaled, vertical rods having bearings for 45 the journals of the sprocket wheels and working up and down through sockets on the main frame, interpivoted levers connected to the journals of the sprocket 50 wheels, means for actuating said levers for the purpose of raising and lowering the frame, and vertical guides connected to said means and working through sockets on the main frame.

55 8. In a street sweeping apparatus, the combination of a main frame, brushes, endless chains carrying the same, sprocket wheels supporting said chains, a vertically-movable frame in which said sprocket 60 wheels are journaled, upright guides hav-

ing bearings that receive the journals of the sprocket wheels and which work up and down in the main frame, links pivoted to the journals of the sprocket wheels, levers pivoted to said links, fulcrums for said levers that project from the main frame, an operating lever and connections between the latter and the said levers by which they are jointly operated.

9. In a street sweeping apparatus, the 70 combination of a main frame, brushes, endless chains carrying the same, wheels supporting said chains, a frame in which the wheels are journaled, vertical rods for the latter frame, sockets on the main frame receiving said rods, levers connected to the journals of the sprocket wheels, means for actuating said levers for the purpose of raising and lowering the frame that carries the wheels, said means including an operating 80 lever, and a counterbalance lever for assisting in holding the brushes to the surface being swept.

10. In a street sweeping apparatus, the combination of a main frame, brushes, endless chains carrying the same, sprocket wheels supporting said chains, a frame in which the sprocket wheels are journaled, guides for the up and down movement of said frame, links connected to the journals 90 of the sprocket wheels, levers fulcrumed on the main frame and pivoted to the upper end of said links, links pivoted to the other ends of the levers, other links connecting the upper ends of said links, pins on said last-mentioned links working through sockets on the main frame, and an operating lever for actuating the aforesaid system of levers.

11. In a street sweeping apparatus, the combination of a main frame, brushes, endless chains carrying the same, sprocket wheels supporting said chains, a frame in which the sprocket wheels are journaled, vertical rods carrying bearings for the journals of the sprocket wheels and sliding in guides on the main frame, links provided with upwardly-projecting pins that slide through sockets on the main frame, connections between said links and the journals of the sprocket wheels, said connections consisting of links and levers, leverage means for raising and lowering the aforesaid system of links and levers, said mechanism including an operating lever, and a counterbalance means for assisting 110 in the movement.

In testimony whereof I hereunto affix my signature.

WALTER S. GUYON.
